UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

MULTICOLOR ROTARY PRINTING PRESS

Application filed November 28, 1930. Serial No. 498,700.

In many instances where the quality of the paper and the character of the forms are such as to permit it, a single web may be printed in multicolor on one side thereof and then in 5 one or more colors on the other side thereof, to perfect the same. In other instances where the quality of the paper and the character of the forms are such as will not warrant the perfecting of the web, the web may be 10 passed through one printing unit to be printed on one side thereof and then cut into sheets and delivered, and when dry the sheets may be perfected in one or more colors by 15 passing them through a sheet feed printing unit for the second printing operation. In other instances it may be desirable to simultaneously print two different webs on one side only thereof.

My invention therefore comprises two 20 multicolor printing units which may be used either together, to perfect a single web, or separately, to print on one side of two webs, manually operated means being employed for connecting and disconnecting the printing 25 units.

My invention also comprises the provision of separate drives for the printing units and their sheet cutting delivery mechanisms as well as the novel arrangement of said delivery mechanisms.

A practical embodiment of my invention is represented in the accompanying drawings, in which:

Fig. 1 represents a diagrammatic side view 35 of a multicolor perfecting printing press with the two printing units operatively connected, to perfect a single web;

Fig. 2 represents a top plan view of the same with the offset device removed;

Fig. 3 represents a view similar to Fig. 1 with the two printing units disconnected for printing on one side only of two webs; and

Fig. 4 represents a top plan view of the same with the offset device removed.

The first printing unit of the multicolor rotary web perfecting printing press is shown as adapted to print up to four colors, the impression cylinder being denoted by 1 and its coacting form cylinders by 2, 3, 4 and 5. In this printing unit the form cylinders are

shown as arranged around the upper side of their impression cylinder.

The second printing unit is shown as adapted to print up to four colors, the impression cylinder being denoted by 6 and its coacting 55 form cylinders by 7, 8, 9 and 10. In this unit the form cylinders are shown as arranged around the under side of their impression cylinder.

The sheet cutting delivery mechanism for 60 the first printing unit is shown as including a pair of coacting rotary cutters 11 and 12 and the sheet cutting delivery mechanism for the second printing unit is also shown as including a pair of coacting rotary cutters 65 13, 14.

These delivery mechanisms are arranged to deliver the sheets flat in piles 15 and 16 respectively, when two webs are being printed on one side only and the delivery mechanism 70 for the second printing unit is arranged to deliver the sheets flat in a single pile 16 only when a single web is perfected by being passed through both printing units.

These delivery mechanisms are arranged at 75 right angles to each other, the delivery mechanism for the first printing unit being located at right angles to the run of the web through its printing unit and the delivery mechanism for the second printing unit being located parallel to the run of the web through its printing unit.

The first printing unit may be provided with a web turner 17 for use in directing its web to the delivery mechanism when such 85 web is not to be perfected by being passed through the second printing unit. This first printing unit may also be provided with a compensating roll 18 around which the web to be perfected is passed on its way to the 90 second printing unit.

The second printing unit may be provided with an offset device for use when a single web is passed through both printing units to be perfected thereby, said offset device being shown as comprising an offset web supply roll 19 from which the offset web 20 may be passed to and around the impression cylinder 6 and from thence to the offset web take-up roll 21.

The means for driving the two printing units and their sheet cutting delivery mechanisms is shown as comprising the following elements:—

- 5 The longitudinally disposed drive shaft 22 for the first printing unit and its delivery mechanism is shown as being driven from an electric motor 23 through a belt and pulley driving connection 24. This shaft 22 drives the first printing unit through the gear train 25. It also drives the delivery mechanism for the first printing unit, through the gear train 26.
- 10 The longitudinally disposed drive shaft 27 for the second printing unit is shown as being driven from an electric motor 28 through a belt and pulley connection 29. This shaft 27 drives the second printing unit through the gear train 30. It also drives the delivery mechanism for the second printing unit through the gear train 31.

- 20
- 25
- 30
- 35
- 40
- 45
- 50
- 55

It is to be understood that the several gear trains connecting the shafts with the parts driven thereby may be of any well known or approved form, suitable for the work intended and, therefore, they will not be specifically described herein.

These two drive shafts 22 and 27 are shown as arranged in alignment with each other and they are adapted to be connected and disconnected by means of a manually operated clutch 32, it being understood that when the shafts are connected they will work together to drive both printing units and their delivery mechanisms and that when the shafts are disconnected the motor 23 may be used for driving the first printing unit and its delivery mechanism and the motor 28 may be used for driving the second printing unit and its delivery mechanism.

In operation: When a single web is to be perfected, both printing units are connected by manipulating the clutch 32, to connect the drive shafts 22 and 27. The web in this instance will be led from its supply roll 33 through the first printing unit and around the compensating roll 18 and through the second printing unit to the cutters 13 and 14 of the second printing unit delivery mechanism where the sheets may be cut from the perfected web and delivered on to the pile 16. In this case the offset web 20 will be used for preventing the freshly printed side of the web from offsetting on to the impression cylinder 6 of the second printing unit.

When two webs are to be printed on one side only or when only one of the printing units is to be used, the two units are disconnected by manipulating the clutch 32 to disconnect the drive shafts 22, 27, thus permitting each motor to be used for driving its particular printing unit and delivery mechanism. Under this condition the web from the web supply roll 33 is passed through the first printing unit, to be printed on one side

thereof, and from thence back and around the turner 17 to the cutters 11, 12 of the delivery mechanism for the said first printing unit, thus causing the sheets printed on one side only to be delivered flat on to the pile 15. 70 The web for the second printing unit is fed from the supply roll 34 under the first printing unit to the second printing unit and from thence to the cutters 13, 14 of its delivery mechanism so that the sheets will be delivered flat, printed on one side only, on to the pile 16. 75

From the above description it will be seen that the two printing units may be used together for perfecting a single web; or that 80 the printing units may be used simultaneously to print on one side only of two webs; or that either one of the printing units may be used alone to print on one side only of a web.

It is evident that various changes may be 85 resorted to in the construction, form and arrangement of the several parts without departing from the spirit and scope of my invention, and hence I do not intend to be limited to the particular embodiment herein 90 shown and described, but

What I claim is:—

1. In a multicolor rotary printing press, two longitudinally aligned printing units operable when connected to print on both 95 sides of one web without changing its longitudinal travel and when disconnected to print on one side only of two webs, and means for connecting and disconnecting said units.

2. In a multicolor rotary printing press, 100 two longitudinally aligned printing units operable when connected to print on both sides of one web without changing its longitudinal travel and when disconnected to print on one side only of two webs, means for connecting and disconnecting said units, and means for driving the two printing units.

3. In a multicolor rotary printing press, 110 two longitudinally aligned printing units operable when connected to print on both sides of one web without changing its longitudinal travel and when disconnected to print on one side only of two webs, means for connecting and disconnecting said units, and a sheet cutting delivery mechanism for each printing 115 unit.

4. In a multicolor rotary printing press, 120 two longitudinally aligned printing units operable when connected to print on both sides of one web without changing its longitudinal travel and when disconnected to print on one side only of two webs, means for connecting and disconnecting said units, a sheet cutting delivery mechanism for each printing unit, and means for driving the two printing units 125 and their delivery mechanisms.

5. In a multicolor rotary printing press, 130 two longitudinally aligned printing units, separate drives therefor, and means for connecting and disconnecting said units whereby they

will, when connected, print on both sides of one web without changing its longitudinal travel and when disconnected, print on one side only of two webs.

6. In a multicolor rotary printing press, two longitudinally alined printing units and their sheet cutting delivery mechanisms arranged at right angles to each other, separate drives therefor, and means for connecting and disconnecting said printing units whereby they will, when connected, print on both sides of one web without changing its longitudinal travel and when disconnected, print on one side only of two webs.

7. In a multicolor rotary printing press, two longitudinally alined printing units operable when connected, to print on both sides of one web without changing its longitudinal travel and when disconnected, to print on one side only of two webs, and means for driving the two printing units comprising two alined longitudinally disposed drive shafts operatively connected to their respective printing units, separate motors for driving said drive shafts, and a manually operated clutch at the adjacent ends of the drive shafts for connecting and disconnecting said shafts.

8. In a multicolor rotary printing press, two longitudinally alined printing units and their sheet cutting delivery mechanisms arranged at right angles to each other, said units being operable, when connected, to print on both sides of one web without changing its longitudinal travel and when disconnected, to print on one side only of two webs, and means for driving the two printing units and their delivery mechanisms comprising two alined longitudinally disposed drive shafts operatively connected to their respective printing units and to their respective delivery mechanisms, separate motors for driving said drive shafts, and a manually operated clutch at the adjacent ends of the drive shaft for connecting and disconnecting said shafts.

9. In a multicolor rotary printing press, two longitudinally alined printing units operable when connected to print on both sides of one web without changing its longitudinal travel and when disconnected to print on one side only of two webs, sheet cutting delivery mechanisms for said printing units, and means for driving said printing units and their delivery mechanisms comprising two alined longitudinally disposed drive shafts, a train of gears connecting each drive shaft with its printing unit and a train of gears connecting each drive shaft with its delivery mechanism, a motor for driving each drive shaft, and a manually operated clutch at the adjacent ends of the drive shafts for connecting and disconnecting said shafts.

10. In a multicolor rotary printing press, two longitudinally alined printing units op-

erable when connected to print on both sides of one web without changing its longitudinal travel and when disconnected to print on one side only of two webs, means for connecting and disconnecting said units, a sheet cutting delivery mechanism for each printing unit, the two delivery mechanisms being disposed at right angles to each other, and a turner for passing a web from the first printing unit to its delivery mechanism, when said delivery mechanism is in use, and means for driving said printing units and their delivery mechanisms.

11. In a multicolor rotary printing press, two longitudinally alined printing units operable when connected to print on both sides of one web without changing its longitudinal travel and when disconnected to print on one side only of two webs, means for connecting and disconnecting said units, a sheet cutting delivery mechanism for each printing unit, the delivery mechanism for the first printing unit being arranged at right angles to the path of the web through its printing unit and the delivery mechanism for the second printing unit being arranged in line with the path of the web through the second printing unit, and a turner for passing a web from the first printing unit to its delivery mechanism, when said delivery mechanism is in use, and means for driving said printing units and their delivery mechanisms.

In testimony, that I claim the foregoing as my invention, I have signed my name this 25th day of November, 1930.

HOWARD M. BARBER.
